2,404,543

INTERNAL-COMBUSTION ENGINE

Robert Steabner, Detroit, Mich.

Application June 22, 1945, Serial No. 600,954

1 Claim. (Cl. 123—51)

1

This present invention relates to internal combustion engines of the type in which two pistons in a single cylinder move away from one another when the fuel charge explodes. The connecting rod of either piston is coupled at the outer end to an end of an oscillating lever the other end of which is connected by a coupling rod to one of the crank portions of a crankshaft.

The object of this invention is the design of an engine which comprises a minimum number of parts that may be produced at low cost and replaced with a minimum of effort.

It is another object of the invention to design an engine that does not rely on the momentum of its moving parts to carry through the dead center.

With these and other objects in view as will appear as the invention is understood, the same resides in the novelty of construction, combination and arrangement of parts described in the following description and claimed in the appended claim. The description should be read in connection with the accompanying drawings in which:

Figure 1 is a vertical section through the longitudinal axis of the cylinder of the preferred embodiment of my invention;

Figure 2 is a horizontal section on line 2—2 of Figure 1;

Figure 3 is a central vertical section on line 3—3 of Figure 1;

Figure 4 is a detail plan view of the central portion of the crankshaft and the coupling rods pivoted thereto as viewed from the plane indicated by section line 4—4 of Figure 1;

Figure 5 is an enlarged detail view of the rocker between the connecting rod of the piston and the coupling rod of the crankshaft.

In the drawings in which like reference characters designate like or similar parts, numeral 2 indicates in general a housing, including parallel, vertical endwalls 3 and a bottom wall 4 comprising inwardly inclined sections and sump 5 located between the inner and lower sides of the bottom sections and intended to collect the oil. The housing also includes a substantially vertical front wall 6 which merges at its lower end into an inclined sump wall and has a slight inward slope at the upper end (Figure 3). The rear wall 7 has a central portion 8 which is outwardly offset with respect to the remainder and slopes near the upper end slightly inwardly and terminates at that end in a vertical flange 9. The top wall 10 consists of a flat horizontally disposed front portion (Figure 3) and side portions sloping out-

wardly (Figure 1). The front portion of the top wall has a vertical flange 11 extending parallel to the flange 9 and said flanges 9 and 11 being disposed to intersect with flanges 12 of the sloping side portions. These flanges have upper edges flush with one another to define an opening for a part of the engine to be described and are provided with bolt holes.

An engine block 13 is secured in the opening 10 within the flanges by bolts 14 inserted in the holes of the flanges and threaded in bosses 15 (Figure 1). The latter are formed at the lower ends of a pair of inclined walls 16 which converge upwardly. At the top end of these walls are bosses 17 with threaded sockets for screw bolts 18 also passing through apertures in a closure plate 19. The intermediate portion of the latter has two openings 20 aligned along the longitudinal axis of the entire engine.

Through the left-hand (Figure 1) opening extends the intake pipe 21 and through the right-hand opening extends the exhaust pipe 22, both shown in dotted lines. The lower and inner end of the intake pipe is threaded into the left-hand portion of the top wall 23 of a valve casing 24, the front wall 25 of which forms a lower portion of the front wall of the engine block. The entire valve casing is symmetrical about a transverse vertical plane indicated by the section line 3—3 of Figure 1 and the description of the left-hand half of the casing and associated parts which commenced in this paragraph will be continued with the understanding that the right-hand half of such casing is a duplicate of the left-hand half except as otherwise stated. The casing has transverse end walls 26, and interior or rear wall 27, a pair of parallel intermediate partitions 28 (Figure 1) and a bottom wall formed by a portion of the cylinder still to be described (Figure 3). The intake pipe communicates with the chamber bounded by the left-hand end wall and partition and portions of the front and rear walls. The left-hand end wall has on either side centrally located bosses 29 with an aperture for the stem 30 of a valve 31. The latter has a conventional bevel on its peripheral margin and is seated in a correspondingly beveled opening in the left-hand partition. The opening of the valve places the chamber described in communication 35 with the explosion chamber between the partitions and below the same to be dealt with later.

The intake valve stem has a portion extending beyond the outer side of the left-hand end wall 26 and carries a transverse pin 32 in the outer 40 end of that portion. The latter is surrounded by

a coil spring 33 bearing with one end against the pin and with the other end against the exterior boss formed on the outer side of that end wall and normally holding the valve to its valve seat.

From the intermediate portion of the bottom wall 34 of the engine block rises a fulcrum post 35 which includes a horizontally extending sleeve 36. A fulcrum pin 37 is journaled in the sleeve and extends beyond either end of the same (Figures 1, 3). Upon the front end portion of such pin is secured a normally downwardly extending arm 38 which has in the lower portion of the side facing the valve stem a groove 39 receiving the outer rounded end of the latter and which opens the valve at the proper time. The rear end portion of the fulcrum pin projecting beyond the rear end of the sleeve is secured to an arm 40 extending upwardly and towards the valve casing and provided upon the upper end portion of the side facing that casing with a groove 41. Into the groove 41 extends the upper rounded end of a rod 42 which is disposed in an inclined position (Figure 1) and is guided in an inclined opening formed in a lug 43 extending from the inner side of the rear wall of the engine block and in the bottom wall of the latter (Figure 3). The portion of the rod below the bottom wall is encircled by a coil spring 44 bearing with its upper end against the lower side of the bottom wall and with its lower end against a washer 45 fixed on the rod.

In the right-hand portion of the valve casing to right of the section plane 3—3 is an exhaust valve and valve operating mechanism both of which are duplicates of the structure just described including the intake valve and the mechanism for operating the same. The exhaust valve and mechanism for operating the same are therefore designated by numerals identical with those used for indicating the intake valve and the mechanism for operating the same.

The two rods for operating the intake and exhaust valves converge downwardly and have lower rounded ends which are engaged in succession by a pair of cams 46 formed on the forward end of a shaft 47. It is understood that the successive operation of the intake and exhaust valves are timed in synchronization with the operation of the engine.

The shaft 47 is journaled in the rear wall of the housing and bearing plate 48 attached to the inner side of the latter and has a head 49 bearing against the outer side of the rear wall. Fixed upon the shaft between the cam structure and bearing plate is a driven gear 50 which meshes at its lower side with a smaller gear 51 rigid upon the crankshaft 52. The latter is journaled in bearing plates 48, each attached to the inner side of the front or rear housing wall respectively, and extends outside of the same. The crankshaft has two cranked sections 53 (Figure 4) which have cylindrical portions 54 journaled in the journal ends of coupling rods 55. The journal ends consist each of a semi-cylindrical half 56 integral with the coupling rod and a semi-cylindrical half 57 secured by a bolt 58 to the first mentioned half. The coupling rods extend in opposite directions and have upon their remote ends journal portions 59 in which pins 60 are journaled.

Rocking levers 61 (Figures 3, 6) are each splined by keys 62 upon a shaft 63 extending parallel to the crankshaft and journaled at the ends in bearing plates 64 attached to the inner sides of the front and rear walls respectively of

the housing. Each rocker consists of an intermediate part 65 having two arms and two outer parts 66 each representing an arm equal in length to an arm of the intermediate part. The outer parts extend in opposite directions and are connected by sleeves 67 to the intermediate part. The sleeve receives the shaft 63 and spaces the outer parts from the intermediate part.

A pin 60 described is mounted in registering apertures formed in the free end of one outer part and of one arm of the intermediate part of a rocker (Figure 2). These parts form the lower arm of each rocking lever. Figure 2 shows that the lower arm of the left-hand rocker is nearer the front wall of the housing and that the corresponding arm of the right-hand rocker is nearer the rear housing wall. The upper arms of these rockers still to be described are aligned with one another.

Figure 1 shows that the straight line connecting the pivot axis of the lower rocker arms in the position shown lies above the axis of the crankshaft. This construction avoids a dead center position, since the angle included by the coupling rod and the crank section connected thereto is less than a straight angle.

The coupling rods rotate the crankshaft and receive their motion by a pin 68 which is mounted in the free end of the other arm of the intermediate part and of the other outer part. Each of such pins 68 is journaled in journal ends 56, 57, 58, similar to the journal ends on the coupling rods and each mounted on the outer end of a connecting rod 69. The other end of each connecting rod pivoted by a wrist pin *w* on to a piston 69 which carries rings *p*.

Both pistons are disposed for motion towards or from one another in a horizontal cylinder 70. The upper portion of which has been described as housing part of the bottom of the valve casing (Figure 1). This upper portion has an opening 71 whereby communication is established between the space in the valve casing bounded by the two valves and the top wall of the valve casing and the interior of the cylinder. The space defined and the interior of the cylinder between the inner portion ends functions as an explosion chamber.

A portion of the cylinder is surrounded by a wall 72 spaced from the cylinder to form therewith a water jacket for cooling the cylinder. The latter is supported by horizontal transverse braces 73 which rest with their outer ends upon the bearing plates described.

The foregoing description describes an engine symmetrical about the section plane 3—3.

The engine is started by a conventional starting motor (not shown) from any position.

Figures 1 and 2 show the pistons in extreme inner positions. The space between the inner ends of the pistons is filled with the charge which has been admitted through the intake valve. As soon as the latter closes, the charge is exploded by the ignition (not shown) and the pistons move away from one another. This motion is transmitted by the connecting rods which swing the upper arms of the rockers outwardly. The coincident inward motion of the lower arm of the rockers causes the cranked section of the crankshaft to rotate a quarter turn at the end of which the crank sections occupy a position slightly inclined to the vertical. Now the exhaust valve is opened by the cam structure described and kept open during the ensuing inward stroke of the pistons which force outwardly through the ex-

haust valve the products of the previous combustion between the inner ends of the piston and the exhaust port. The latter closes as the cam shaft is rotated and the inlet port is opened by one of the cams and a charge is drawn into the cylinder. This charge explodes at the beginning of the next quarter turn. This cycle is repeated. The broad idea of my invention, as defined in the appended claim, may of course, be carried out in structures varying from that herein specifically described, so that the details which I have disclosed in the foregoing description and accompanying drawings to illustrate a preferred embodiment of my invention are not to be taken as limitative.

I claim:

An internal combustion engine comprising a frame, an engine block in the upper portion of

the frame, a cylinder in the engine block, inlet and exhaust valves normally closed in the engine block above the cylinder, a pair of pistons in the cylinder, a pair of connecting rods, each connected to a piston, a pair of rocking levers pivoted in the frame and each having one arm connected to a connecting rod, a pair of coupling rods each connected to the other arm of a lever, a crankshaft journaled in the frame and having a pair of cranks each connected to the other end of a connecting rod, a shaft journaled in the frame and geared to the crank shaft, cams on the shaft, a pair of rods slidably mounted in the frame and successively operated by the cams, and levers fulcrumed in the engine block and each coacting with a rod for opening a valve.

ROBERT STEABNER.
